UNITED STATES PATENT OFFICE

91,396

DESIGN FOR A CABINET FOR CASH REGISTERS

James Douglas Lorenz, Dayton, Ohio

Original application October 8, 1932, Serial No.
45,259. Divided and this application October
30, 1933. Serial No. 49,593

Term of patent 14 years

To all whom it may concern:

Be it known that I, JAMES DOUGLAS LORENZ, a citizen of the United States of America, residing at Dayton, in the county of Montgomery, State of Ohio, have invented a new, original, and ornamental Design for a Cabinet for Cash Registers, of which the following is a specification, reference being had to the accompanying drawings, forming part thereof.

Fig. 1 is a perspective view of a cabinet embodying the design;

Figs. 2, 3 and 4 show a front, side and rear elevation respectively thereof, on reduced scale, the keys being omitted from the showing of Fig. 2 for purposes of simplicity in illustration.

This case is a division of my copending appli-

cation design Serial No. 45,259 filed October 8, 1932 for Cabinet for cash registers.

The design is illustrated in the drawings, as embodied in a cabinet, having a base, side and back walls, and a front wall which has the keyboard set therein. The cabinet surfaces are discontinuous and have breaks, set-backs, offsets and panel effects to give an accentuated tapering appearance to the cabinet from the base toward the top. The several walls, the base and the keyboard are preferably of contrasting materials, finishes or colors.

I claim:

The ornamental design for a cabinet for cash registers, substantially as shown and described.

JAMES DOUGLAS LORENZ.
